COMBINATION ANTIRAIL CREEPER AND
FASTENERSardine Stone and Clarence W. Weldner,
Columbus, Ohio

Application November 20, 1935, Serial No. 50,765

2 Claims. (Cl. 238—349)

The invention relates to a railway rail fastener and more especially to a combination anti-rail creeper and fastener.

The primary object of the invention is the provision of a device of this character, wherein a railway rail will be held against creeping and will be anchored upon a cross tie so as to prevent the spreading of the rail as well as eliminating the shearing of spikes resultant from vibrations or the kicking of the rail when servicing rolling stock, the rail being anchored and held solidly fastened to a cross tie.

Another object of the invention is the provision of a device of this character, wherein through the use of a plate made secure to a cross tie a railway rail can be conveniently seated in said plate and fastened so as to avoid spreading of the rail, creeping thereof or vibration being set up when rolling stock is passing over the same, the device being of novel construction and assuring a solid fastening of such rail in place upon the cross tie.

A further object of the invention is the provision of a device of this character, which is simple in its construction, thoroughly reliable and efficient in its purposes, strong, durable, readily and easily applied with dispatch, avoiding the use of spikes and inexpensive to manufacture and install.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is a fragmentary perspective view of a railway rail and cross tie showing the device constructed in accordance with the invention applied.

Figure 2 is a fragmentary sectional view on the line 2—2 of Figure 1 looking in the direction of the arrows.

Figure 3 is a perspective view of one of the clamp plates employed with the device.

Figure 4 is a perspective view of another of the clamp plates.

Figure 5 is a view similar to Figure 2 showing a slight modification.

Figure 6 is a bottom plan view of one of the clamps employed in the modified form shown in Figure 5.

Similar reference characters indicate corre-

sponding parts throughout the several views in the drawing.

Referring to the drawing in detail, particularly Figures 1 to 4 inclusive, A designates generally a portion of a cross tie and B a portion of a railway rail, these being of the usual or well-known construction. Interposed between the tie and the rail is a metal plate 10 having intermediate thereof at its upper face vertical flanges 11 which are spaced from each other correspondingly to the width of the base 12 of the rail which latter is superimposed upon this plate 10 to have its base snugly held between the upstanding flanges 11 thereof.

The flanges 11 are reinforced by thickened portions 13 formed on the plate 10 and integrally joined with the said flanges 11 at the outer sides thereof, the flanges being of greater height than the thickened portions 13 and are cut away to provide gaps 14 midway of their length. 20

The plate 10 is placed upon the top of the tie A and is made secure by headed bolts 15, these passing through two suitable apertures therefor as provided in said plate 10 and are screwed or otherwise anchored in the tie A. The bolts 15 25 are disposed outwardly with respect to the thickened portions 13.

Occupying one gap 14 in the flange 11 is a clamp 16 of substantially T-form which overhangs the base 12 of the rail B at one side of the latter 30 and overlaps the thickened portion 13 of the plate 10 next thereto, the clamp 16 being provided with an elongated slot 17 matching a similar slot 18 provided in the thickened portion 13 of the plate 10. These slots 17 and 18 accommodate a headed bolt 19 which is screwed or otherwise made fast in the tie A while between the head of the said bolt and the clamp 16 is disposed a lock washer 20. By the slots 17 and 18 in the clamp 16 and the plate 10 suitable adjustment of such plate 10 and the clamp 16 can be had, it being understood, of course, that for the adjustment of the plate 10 the bolts 15 are free from fastening engagement with the tie A. 40

The other gap 14 accommodates a substantially elliptical shaped washer 21 which overhangs the base 12 of the rail B at the other side thereof and the thickened portion 13 next thereto while passed through this washer 21 is a headed bolt 22, it being received in the elongated slot 23 50 formed in the thickened portion 13 of the plate 10 immediately below the location of the said washer. It is preferable to have the clamp 16 and the washer 21 upwardly bowed to assure a firm clamping action of these upon the 55

base 12 of the rail B on the working of the headed bolts home in the tie A.

In Figures 5 and 6 of the drawing there is shown a slight modification wherein the substantially T-shaped clamp 24 at its under side is formed with a nib 25 constituting a T for engagement in a seat 26 provided in the thickened portion 27 of the plate 28, the nib being provided with a beveled face 29 coacting with a beveled wall 30 in the seat 26 and this wall coincident with the beveled face 29 inclines toward the base of the rail so that when the clamp 24 is screwed down the tendency of the nib 25 working against the wall 30 is to move the clamp onto the base 15 of the rail. The nib 25 next to the base of the rail is cut to form a jaw 31 for engaging the edge next thereto of the base of said rail. The clamp 24 is used at one side of the rail only while the washer 32 is used at the other side for clamping the base of the rail.

The headed bolt 22 is fitted with a lock washer 33. The headed bolt 34 employed with the clamp 24 passes through a slot 35 in said clamp and in a hole or opening 36 in the thickened portion 27 of the plate 28 and thus by this slot 35 the clamp 24 can be shifted under the action of the nib 25 working against the wall 30 of the seat 26 in said plate 28.

In the use of the device the rail is solidly fastened to the tie A and such rail is prevented from creeping or spreading and firm anchorage of this rail is assured without the use of spikes.

The headed bolts are fastened in the tie A. The rail B can be readily aligned and set to the proper gage with respect to an opposite rail in the use of the device and in such use it affords an anti-rail creeper, a rail anchor and an anti-track spreader.

The clamp 24 is of the T-form similar to the clamp 16.

What is claimed is:

1. A device of the kind described comprising a plate adapted for mounting upon a cross tie 5 and having spaced openings therein, upstanding flanges on said plate arranged in spaced parallel relation to each other for accommodating therebetween a base of a rail, enlargements on said plate outside of the flanges and joined therewith, springy clamps interfitting with the flanges and extending over the base of said rail, fasteners passed through the clamps and the openings in said plate and engaged in the tie, the said plate being formed with a beveled wall, and a 15 beveled nib formed on one of the clamps and coacting with the beveled wall of the plate.

2. A device of the kind described comprising a plate adapted for mounting upon a cross tie and having spaced openings therein, upstanding 20 flanges on said plate arranged in spaced parallel relation to each other for accommodating therebetween a base of a rail, enlargements on said plate outside of the flanges and joined therewith, springy clamps interfitting with the flanges 25 and extending over the base of said rail, fasteners passed through the clamps and the openings in said plate and engaged in the tie, the said plate being formed with a beveled wall, a beveled nib formed on one of the clamps and coacting 30 with the beveled wall of the plate, and means fastening the plate to the tie and independent of the fasteners engaged in said clamps.

SARDINE STONE.
